TRAY ATTACHMENT MEANS

Clarence Roland Veal, Albany, Oreg.

Application February 11, 1938, Serial No. 190,098

1 Claim. (Cl. 155—127)

This invention appertains to new and useful improvements in furniture and more particularly to a high chair tray and attaching means therefor.

5 The principal object of the present invention is to provide attaching means for high chair trays of such construction as to make it practically impossible for the infant to loosen the tray.

Still another important object of the invention 10 is to provide a safe and substantially fool-proof detent for high chair trays which will be of simple construction and of low cost to manufacture.

Other important objects and advantages of the 15 invention will become apparent to the reader of the following specification.

In the drawings:

Figure 1 represents a fragmentary side elevational view of a high chair equipped with the 20 novel tray structure.

Figure 2 represents a fragmentary inside elevational view of one of the arms of the chair.

Figure 3 is a sectional view taken substantially 25 on the line 3—3 of Figure 1.

Figure 4 is a top plan view of the attaching means detached from the tray with parts in section.

Figure 5 is a sectional view on the line 5—5 of 30 Figure 4.

Figure 6 is an edge elevational view of one of the latch members.

Figure 7 is a perspective view of the pivotal catch.

Figure 8 is a perspective view of one of the connecting rods.

Figure 9 is a perspective view of one of the keeper plates.

Figure 10 is a plan view of the operator.

Figure 11 is an edge elevational view of the 40 operator.

Referring to the drawings wherein like numerals designate like parts, it can be seen in Figure 1, that numeral 5 generally refers to a high chair which includes the legs 6 depending from the seat 7 and also the back 8 and props 9 supporting the armrest 10.

These armrests 10 each at its inner side is, as shown in Figure 3, provided with a longitudinally extending slot 11 opening into a channelway 12 45 in which is secured an elongated keeper plate 13 provided at equally spaced intervals with openings 14.

Numerals 15 represents the tray which includes the bottom 16 and side walls 17. A plate 18 is 50 suitably secured to the bottom of the tray 15 and

has the pocket 19 therein for receiving the operator 20 which is provided with a laterally extending arm 21 provided at its outer end with the downwardly disposed finger engageable lip 22. The periphery of the plate 20 is notched to define the shoulder 23 against which the lip 24 on the arm 25 of the pivotal catch 26 is engageable. This catch 26 is provided with the longitudinally extending flange 27 between which and a portion of the plate 18 a coiled compressible spring 28 is 10 interposed for normally maintaining the lip 24 engaged against the periphery of the operator 20 and in the path of the shoulder 23.

The end portions of the plate 18 are pocketed as at 29 for receiving the detent arms 30. Each 15 of these arms consists of an elongated member 31 having upwardly disposed portions 32—32 with an ear 33 extending from one of these portions 32 and apertured to receive the pivot member 34 and its opposite end being provided with the extension 35 laterally from which extends the tooth 36 for engagement into the corresponding opening 14 of the corresponding keeper plate 13.

A connecting rod 37 provided with laterally disposed end portions 38 is provided for each of the 25 detents 30, one end of the connecting rod being engaged with the extension 35 of the corresponding detent 30 while its opposite end is engaged into the corresponding slot 39 of the operator 20.

A spring member 40 has its ends connected to 30 the upwardly disposed portions 32—32 of each of the detents 30 and each of the pockets 29 is provided with a boss formation 41 normally bearing against the corresponding spring member 40. Thus, the teeth 36 are normally projected into 35 the openings of the keeper plate 13. Normally the operator 20 is prevented from operation by the catch plate 26 and the operator 20 can only be operated by first gripping the catch 26 and swinging the same so as to disengage the lip 24 40 from the shoulder 23 so that the operator is freed and can be swung to retract the teeth 36 from the keeper plates 13.

It can also be seen that the end portions of the plate 18 are reduced as at 42 for sliding disposition in the slotways 11.

While the foregoing specification sets forth the invention in specific terms, it is to be understood that numerous changes in the shape, size and materials may be resorted to without departing from 50 the spirit and scope of the invention as claimed hereinafter.

Having described the invention, what is claimed as new is:

In combination, a high chair including arms, 55

keeper means on the inner sides of the arms, a tray, latch means on the tray including detents swingably mounted thereon for engagement with the keeper means on the arms, a rotatable operator on said tray operatively connected to the 5 detents to engage and disengage the same, and having a shoulder thereon, a catch for the opera-

tor having a lip thereon for engagement with the shoulder to prevent operation of the operator, said catch being mounted on the tray and operative to disengage the lip from the shoulder, and spring means tensioning said catch against such 5 operation.

CLARENCE ROLAND VEAL.
